(57) **CLAIM**

I claim the ornamental design for a smart holder for mobile phone or camera, as shown and described.

DESCRIPTION

FIG. 1 is a perspective view of a smart holder for mobile phone or camera, showing my new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a reference view thereof showing a configuration of use; and,
FIG. 9 is another reference view thereof showing another configuration of use.
